UNITED STATES PATENT OFFICE.

JOSEPH FREDERICK, OF STROUDSBURG, PENNSYLVANIA.

PNEUMATIC HAMMER.

No. 891,831.

Specification of Letters Patent. Patented June 30, 1908.

Application filed January 22, 1908. Serial No. 412,173.

To all whom it may concern:

Be it known that I, JOSEPH FREDERICK, a citizen of the United States, residing at Stroudsburg, in the county of Monroe and State of Pennsylvania, have invented a new and useful Pneumatic Hammer, of which the following is a specification.

This invention relates to pneumatic tools of that general class employed for cutting, 10 calking or riveting in metal or stone work or for plugging and like purposes.

The principal object of the invention is to provide a tool of very simple construction in which the air or other actuating fluid is supplied to both ends of the cylinder and is exhausted from both ends of the cylinder separately, all of the ports, both inlet and exhaust, being under control of the piston or plunger.

A further object of the invention is to form 20 the piston with a plurality of circumferential fluid receiving grooves or ports which register with the inlet ports and thus admit a small quantity of air to the opposite ends of the cylinder for the purpose of cushioning the 25 piston as the same reciprocates.

A further object is to provide the inlet port with a plurality of branch passages which open through the cylinder and are spaced a uniform distance apart around the piston so 30 that the air will be directed radially of the piston and thus perfectly balance the same.

A still further object of the invention is generally to improve this class of devices so as to increase their utility, durability and efficiency.

Further objects and advantages will appear in the following description, it being understood that various changes in form, proportions and minor details of construction 40 may be resorted to within the scope of the appended claims.

In the accompanying drawings forming a part of this specification: Figure 1 is a sectional elevation of a pneumatic tool constructed in accordance with the present invention, the piston being shown starting on its working stroke. Fig. 2 is a sectional view of the tool with the handle removed showing the piston starting on the return stroke. Fig. 3 is a transverse sectional view taken on the line 3—3 of Fig. 1. Fig. 4 is a sectional view taken on the line 4—4 of Fig. 1. Fig. 5 is a transverse sectional view taken on the line 5—5 of Fig. 1. Fig. 6 is a similar view 55 taken on the line 6—6 of Fig. 1. Fig. 7 is a

perspective view of the plunger or piston removed.

Similar numerals of reference indicate corresponding parts in all of the figures of the drawings.

The improved hammer forming the subject matter of the present invention comprises a handle 10 having a spring closed valve 11 which controls an inlet port 12 extending through the handle, as shown.

The handle is provided with a forwardly projecting neck 13 having a threaded socket 14 for the reception of the threaded end of the cylinder 15, while the neck 13, which is split, extends over a portion of the cylinder proper and is clamped in place by a bolt 16.

The end of the cylinder opposite the handle 10 is provided with a suitable tool socket 17 which receives the shank of a chisel, hammer, riveting or other tool illustrated at 18.

The bore 19 of the cylinder is of uniform diameter throughout and leading from this bore are exhaust ports 20 and 21, one near the handle end and the other near the socket end of the cylinder, said exhaust ports passing directly through the wall of the cylinder to permit the escape of air or other actuating fluid.

The main air passage or inlet port 12 is provided with a plurality of branch passages 22 preferably four in number, as shown, and which extend downwardly through the side walls of the cylinder and are placed in communication with the bore of said cylinder through ports 23 and 24, there being four 80 ports 23 near the handle of the cylinder, and four ports 24 near the tool socket end of the cylinder, all of said ports being under the control of the piston or plunger 25.

Attention is here called to the fact that the ports 23 and 24 open into the cylinder around the piston 25 and are spaced a uniform distance apart so that air under the same pressure will be directed radially of the piston and thus perfectly balance the same.

Near the handle end of the cylinder are arranged two ports 26 which communicate at one end with the bore of the cylinder adjacent the handle thereof and at the opposite end communicate with the bore of the cylinder at a point in alignment with the ports 23, the ports 26 constituting bypasses through which the air may pass from the port 23 to the handle end of the cylinder when the piston or plunger is in the position shown in Fig. 110

1 in order to furnish the desired pressure for the working stroke.

At the tool socket end of the cylinder are arranged two by-pass ports 27, the outer ends of which communicate with the outer end of the cylinder at a point adjacent the socket 17, while the inner ends of said by-pass ports communicate with the bore of the cylinder at a point in alinement with the ports 24.

The by-pass ports 27 permit the passage of air from the ports 24 to the outer end of the cylinder when the piston is in extended position, as best shown in Fig. 2 of the drawings.

15 The piston 25 is provided with an intermediate annular groove 28 which, when the piston is positioned within the bore of the cylinder forms a circumferential fluid receiving chamber 29.

20 Disposed on each side of the intermediate groove 28 is an auxiliary cushioning groove 30 which registers with the ports 23 and 24 when the piston is reciprocated and serves to permit a small portion of the air from the ports 22 and 24 to flow through the by-passes 26 and 27 to the opposite ends of the cylinder thereby to form a cushion for the piston.

25 The grooves 30 not only allow a small quantity of air under pressure to pass to the opposite end of the cylinder for the purpose of forming a cushion at each end of the piston, but also form a fluid pressure packing for the side walls of the piston.

30 In operation, the valve 11 being open and the piston in the position shown in Fig. 1 of the drawings air will flow through the port 15 and fluid passages 22 to the ports 23 into the chamber 29 and thence through the by-passes 26 to the head of the cylinder where it 35 acts on the piston or plunger and forces the latter outwardly to the position shown in Fig. 2 of the drawings, the piston or plunger being forcibly driven against the tool. During the out stroke the plunger covers the ports 23 and uncovers the exhaust port 20, the latter being opened just in advance of the completion of the working stroke of the piston so that the air in the working end of the cylinder may escape. As the piston is 40 forced in contact with the tool 18 the adjacent annular groove 30 will register with the ports 23 and thus allow a portion of the air to flow through the by-passes 26 to the handle end of the cylinder so as to give an additional impulse to the piston, a portion of the air being retained in the groove 30 so as to form a fluid packing for the walls of the piston, in the manner before stated. When the piston moves to the opposite end of 45 the cylinder and completes its working stroke the ports 24 will be placed in communication with the by-pass ports 27 and sufficient air will pass to the outer end of the cylinder to return the piston to the initial

50 retracted or returned to normal position the adjacent groove 30 will register with the port 23 and thus allow a portion of the air from the feed passage 12 to flow through the by-passes 26 to the rear of the cylinder thus forming a cushion for the piston, a further rearward movement of the piston uncovering the ports 23 and allowing the air to pass through the passages 27 and move the valve in engagement with the tool, in the manner 55 before stated. It will thus be seen that the grooves 30 not only permit a portion of the air to enter at the rear of the cylinder to form a cushion for the piston but also permits an additional impulse to be imparted to the 60 piston after the latter had been started on its working stroke. It will also be noted that by forming the inlet port with a plurality of fluid passages arranged at equal distances apart on the interior of the cylinder an 65 equal pressure is exerted on all sides of the piston so that the latter is perfectly balanced and the efficiency of the tool materially increased.

70 While there is shown and described four fluid ports opening into the cylinder at each end thereof, it will of course be understood that the number of ports may be varied without departing from the spirit of the invention.

75 Having thus described the invention what is claimed is:

1. In a pneumatic tool, a cylinder, independent inlet ports arranged at each end of the cylinder, a piston having a peripheral groove forming a port which co-acts with the inlet ports at both ends of the cylinder for controlling the supply of fluid, by-pass ports leading from the inlet ports to the adjacent ends of the cylinder, and means for permitting the passage of a portion of the fluid through the by-pass ports after the piston has started on its working stroke.

2. In a pneumatic tool, a cylinder, a feed port having a plurality of fluid passages communicating therewith and provided with inlet ports opening through the bore of the cylinder at equal distances around the wall thereof, a piston mounted for reciprocation within the cylinder and having an intermediate peripheral groove forming a port which co-acts with the inlet ports for controlling the supply of fluid, and auxiliary grooves formed in the piston one on each side of the intermediate groove and adapted to register with the inlet ports to permit the passage of air to the adjacent ends of the cylinder after the latter has started on its working stroke.

3. In a pneumatic tool, a cylinder, independent ports arranged at each end of the cylinder, a piston mounted for reciprocation within the cylinder and provided with a port which co-acts with the inlet ports at both ends of the cylinder for controlling the supply of fluid, auxiliary ports arranged in

the piston and adapted to register with the inlet ports in the cylinder thereby to permit the passage of air to the adjacent ends of the cylinder to form a cushion on each stroke of 5 the piston.

4. A pneumatic tool including a cylinder having at each end a by-pass port, both ends of which communicate with the bore of the cylinder, a feed port also communicating 10 with the bore of the cylinder at a point substantially in alinement with the inlet end of the by-pass port, a piston having a main port or passage for placing the inlet port in communication with such by-pass port at each 15 end of the piston stroke, and auxiliary ports formed in the piston and adapted to register with the inlet ports to admit a small quantity of air to flow to the adjacent end of the cylinder to form a cushion.
- 20 5. In a pneumatic tool, a cylinder having by-pass ports at each end thereof, feed ports communicating with the bore of the cylinder at points in alinement with the inner ends of said by-pass ports, a handle member 25 having a valve passage with which said feed ports communicate, a piston having a main port or passage co-acting with the feed ports to permit the flow of air through the by-pass ports to the cylinder, auxiliary ports formed 30 in the piston one on each side of the main port and adapted to register with the inlet ports of the cylinder to admit a small quantity of air to each end of the cylinder, and piston controlled exhaust ports leading from 35 both ends of the cylinder.

6. In a pneumatic tool, a cylinder, a handle, a feed passage leading through the handle to the end of the cylinder, a piston

mounted for reciprocation within the cylinder, a plurality of branch passagés communicating with the feed port and provided with inlet ports opening through the walls of the cylinder at equal distances apart for directing the air radially of the piston, by-pass ports arranged at the end of the cylinder, 45 each end of each by-pass port communicating with the bore of the cylinder, the inner ends of the by-pass port being in transverse alinement with the feed port, there being a circumferential groove formed in the piston that controls communication between the feed ports and by-pass ports, auxiliary grooves formed in the piston and adapted to register with the inlet ports thereby to admit a small quantity of air to the adjacent end of 50 the cylinder, and independent piston controlled exhaust ports leading from the opposite ends of the cylinder.

7. In a pneumatic tool, a cylinder, inlet ports arranged at each end of the cylinder, a piston for controlling the supply of fluid through said ports, by-pass ports leading from the inlet ports to the adjacent ends of the cylinder, and a port formed in the piston and adapted to register with the inlet ports 60 thereby to admit a relatively small charge of fluid through the by-pass ports to the adjacent end of the cylinder after the latter has started on its working stroke.

In testimony that I claim the foregoing as 70 my own, I have hereto affixed my signature in the presence of two witnesses.

JOSEPH FREDERICK.
